Primary Examiner — Eliza Z Harvey*Assistant Examiner* — Adrian A Shwaiko(74) *Attorney, Agent, or Firm* — Steve LeBlanc, LLC(57) **CLAIM**

The ornamental design for a blade, as shown and described.

DESCRIPTION

FIG. 1 is a left, front perspective view of the blade embodying the new design;

FIG. 2 is a left side elevation view of the blade;

FIG. 3 is a right side elevation view of the blade;

FIG. 4 is a top side elevation view of the blade;

FIG. 5 is a bottom side elevation view of the blade;

FIG. 6 is a front side elevation view of the blade; and,

FIG. 7 is a rear side elevation view of the blade.

The dash-dash broken lines shown in the drawings depict portions of the blade that form no part of the claimed design. The dash-dot-dash broken line is included for the purpose of illustrating the bounds of the claim and form no part of the claimed design.

1 Claim, 5 Drawing Sheets(56)
